BASE SUPPORT FOR FURNITURE OR SIMILAR ARTICLE

Dieter F. Wegner, 11628 W. Shorecliff,
Mequon, Wis. 53092

Filed May 13, 1969, Ser. No. 17,140

Term of patent 14 years

Int. Cl. D6—01

U.S. Cl. D33—14

FIG. 1 is a top view of a base support for furniture or similar article embodying my design.

FIG. 2 is a side elevation view taken on line 2—2 of FIG. 1.

FIG. 3 is a side elevation view taken on line 3—3 of FIG. 1.

FIG. 4 is a cross section taken on line 4—4 of FIG. 3 showing one form of the legs for the base support.

FIG. 5 is a cross section similar to FIG. 4 showing another form of the legs for the base support.

FIG. 6 is a cross section similar to FIG. 4 showing another form of the legs for the base support.

I claim:

The ornamental design for a base support for furniture or similar article, as shown.
